UNITED STATES PATENT OFFICE.

LEON ROSSITER DALGLISH STAHL, OF EAST MELBOURNE, REGINALD GEORGE WILSON, OF PARKVILLE, AND WALTER REGINALD TERRY AND DOUGLAS MUNRO HULL, OF MELBOURNE, VICTORIA, AUSTRALIA.

HOLDING AND PRINTING MECHANISM FOR WRAPPING PAPER AND OTHER ROLLS.

Application filed November 3, 1925, Serial No. 66,452, and in Australia August 15, 1925.

This invention relates to mechanism whereby the web of a roll of sheet material, such as wrapping paper used in shops, will be printed upon as it is being withdrawn 5 from the roll. Advertisements and/or other notifications may thus be put on the wrappers before the latter are made to enclose goods.

Our improvements relate to the machine 10 frame and to the inking and printing mechanisms. The frame carries all the parts conveniently, each of various rollers of this machine being easily changeable for another. The ink will not leak from its reservoir, and 15 frequent renewal of ink will not be required.

The colour or colours of ink can be varied.

Our machine will operate as a counter 20 adjunct, and allow of easily drawing out the paper and tearing it off, leaving an edge 25 of paper ready for grasping when the next withdrawal occurs. Any desired length of paper may be drawn from a roll in contact with the printing roller or rollers, before severing. The severing need not be for 25 wrapping purposes; as paper is, when printed on suitably, often of use to make a window frieze, or background, or for other purposes.

Construction according to this invention 30 is herewith illustrated, but details may be modified while retaining any combination hereinafter claimed.

In the drawings, Figure 1 is a side sectional view of the machine.

Figure 2 is a front view partly in section 35 of the machine equipped with two rolls of paper, and with an inking and printing device for each roll.

Figure 3 is a side sectional view of part 40 of Figure 1, but set in a different position, which will permit of removal of the printing roller, or if desired the said roller and parts under it.

Figure 4 is a perspective view of part of 45 the inking mechanism.

The machine has a main frame formed by cheeks 1, 1^a, connected and spaced apart by bars of which three, 2, 2^a, 2^b are shown, either cheek being removable, by unscrewing 50 the end fastenings which are shown as nuts 2^a, on the said bars. This frame has feet which are adapted to rest and stand firmly on glass or other polished surfaces,

and also adapted to allow the machine to be slid into other positions without damaging the glass or other supporting surface. Thus on the underside of each foot is a pad 1^b, which may be of rubber.

At an upper front part of the machine, that is facing the operator each cheek has a bearing, the entrance to which is a slot 1^c, Figure 1, carrying the end of a removable spindle 3, herein called the main spindle, which carries the paper roll or rolls.

We show two rolls 4, 4^a, and to align these 65 with their printing mechanisms we provide 70 slidable means of suitable form, shown as members 5 and 6. Thus the member 5 has apertures through which extend the spindle 3, and the bars 2, 2^a, 2^b. Through the member 6 which is small, only the spindle 3 extends. Member 5 and member 6 will be each set abutting against a roll of paper, as in Figure 2, to prevent the latter sliding out of printing alignment; but members 5, 6, 75 may if desired be set at either side of the main frame, or one at each side abutting against a cheek.

When only one paper roll is in use, but 80 needs to be prevented from sliding, one alignment member will suffice, either a plate 5 or a member 6. The plate 5 is shown 85 abutting against the roll 4^a, and the member 6 against the roll 4, keeping these paper rolls in alignment with their printing rollers. Plate 5 has the further advantage that when a cheek is removed it will retain the bars 2, 2^a, and 2^b, in their relative positions, and will thus facilitate the replacement of the cheek, whether the spindle 3 has been 90 removed or not. Plate 5 has a perforated lug 5^a carrying a set screw 5^b extending through the perforation to grip the spindle; member 6 has also adjustment means shown as a pin 3^a inserted in a hole in the spindle, 95 which has sufficient holes for selection purposes.

We provide at the frame rear a trough or troughs 8, two being shown in Figure 2. These are slidably supported on the bars 2, 100 2^a, which are parallel. This trough has at its lower part means, shown as eyes 8^a, engaging the bar 2, and has at its upper part means, shown as a clip 8^b which frictionally grips the upper bar 2^a, but is detachable therefrom by hand pressure. On detaching the 105

- clip as in Figure 3, the trough top will swing rearward, and thus permit an attendant to have easy access to the trough contents. We find it to be convenient to make the 5 trough with cast metal ends 8^c, each carrying an aforesaid eye 8^a, the walls and base of the trough being of sheet metal secured to the ends, the front wall being provided with the said clip 8^b which may be integral.
- 10 The trough base is its ink-containing part, and means are provided to limit the amount of ink therein. Thus a passage 9 having an escape opening 9^a is shown at a suitable level. This opening and passage (the top of 15 the latter being shown wide) are usable for replenishing the ink. 9^b indicates a closing cap.

Above the ink well at the trough base, the trough contains ink distributing means. 20 Within the trough and at each end thereof is a guide formed, for example, by a channel between two ribs 10. The guides receive the ends of a slidabé frame 11, called herein the printing roller frame, the upper part of 25 which has bearings 11^a engaged by the spindle 7^a of a printing roller 7. Under frame 11 is a spring 12 of, for example, semi-elliptic form, the spring limbs resting upon the trough floor, and the spring middle attached to the frame. The frame 11 contains 30 a smaller, called herein the innermost, frame 13, under which is a spring 14 of, for example, semi-elliptic form, the limbs of which rest on the base of the frame 11. The innermost frame carries ordinarily extending 35 upward from its lower part, an ink distributing means of wick type. Thus 15 is a wick; its lower part dipping into the ink in the trough; its upper part extending into 40 contact with a transversely extending ink transfer roller 16, of any suitable material, which is carried by frame 13. As a roller material we find that it is advantageous to use comparatively soft wood enclosed in an 45 absorbent sheath made of spirally wound fabric, marked 16^a. This roller has a rotatable spindle 16^b, and above this roller is the aforesaid printing roller 7 which has a printing face 7^b of any suitable material, as 50 rubber. The effect of springs 12 and 14 is to press the printing roller frame 11 and the innermost frame 13 upward.

There may be employed a ready inked 55 roller, if desired, instead of the transfer roller 16 as the use of a ready inked roller would facilitate printing in any colour not in the ink well, the wick not then being necessary. If a ready inked roller be employed it may advantageously be made of 60 soft wood sheathed as described with reference to roller 16; or either roller may be made of discs or washers of suitable material, as felt, strung close together on a spindle, and if desired sheathed. When the 65 sheath has a spiral joint, and is made of

such material as thin felt, the effect is to cause uniform or nearly uniform transfer of ink to the printing roller.

A very useful machine according to our invention can be made of simple form having only one paper roller and one inking and printing means, but the inking and printing means illustrated in Figure 2 permit of printing in a plurality of colours, whether there be two paper rolls or only 70 one. We could use to contain different coloured inks, a wide trough partitioned; but we illustrate two troughs, each narrow enough to allow of its being slid transversely to any desired working position.

Above the or each printing roller is an abutment roller 17 which is in one piece or is formed in sections, so that any section can be independently rotated. This roller has a spindle 17^a supported in bearings 17^b in cheeks 1, 1^a.

As the mechanism which is located below the abutment roller is subject to the upward pressure of the springs 12 and 14, the said mechanism rises as high as the abutment 90 roller allows; and as the paper from the source provided as the roll is made to pass between the abutment roller and the printing roller, the paper will therefore become 95 printed on by the contacting roller 7 as the paper is moved along.

In practice the paper is drawn out, as shown in Figure 1 by broken lines, from the roll and is passed under the abutment roller, then above the latter, and then to a 100 guide which is provided, shown as a roller 18, over which the paper is drawn past the edge of a blade 19, termed the tearing blade. This blade is supported at the front of the machine by the side bars 20 of a small light 105 top frame which has suitable pivotal supports such as the bearings of the abutment roller 17. This top frame can be easily grasped by being swung upward, as per the arrow in Figure 1. This top frame consists of the parts 18, 19, and 20. It extends above, and is supported at its front by the roll of paper, normally; but when raised by swinging it as per arrow A, it is moved 110 clear of the paper roll which can then be changed. This top frame carries paper retaining clips 21 above guide roller 18, to 115 press on the paper and keep it in alignment, the clips holding the paper against the said roller.

As the roller 18, which rests on the paper roll, is easily rotatable by friction, the unrolling of the paper required from time to time will not be materially impeded. A 120 tearing blade 19 of any suitable detail, as one with a bevelled edge of well-known type, is usable.

It is now obvious that when this machine 125 is in use various rollers will by frictional contact rotate when an attendant grasps and 130

pulls the paper by seizing its edge 4^e; that is the printing roller 7 will rotate, and will receive ink from transfer roller 16 or the like, which will rotate.

5 We claim:—

1. In paper holding and printing mechanism, a movable trough to contain ink in its lower part, guiding means at the ends of the trough, a frame carrying a printing roller and having ends engaged by the said guiding means, means under the said frame which press the said frame upward, an innermost frame carried by the printing roller frame, and fitted with an inking roller, and means which press the innermost frame upward to cause the inking roller to bear against the printing roller.

2. In paper holding and printing mechanism, a movable trough to contain ink in its lower part, guiding means at the ends of the trough, a frame carrying a printing roller and having ends engaged by the said guiding means, means under the said frame which press the said frame upward, an innermost frame carried by the printing roller frame, and fitted with an inking roller, and means which press the innermost frame upward to cause the inking roller to bear against the printing roller,

30 the trough being supported by upper and lower bars which extend transversely of the

machine, the trough lower support being pivotal, the upper support being by detachable clipping, the effect of detachment being to allow the trough top to swing rearwardly and be exposed for the purposes set forth.

3. In paper holding and printing mechanism, a movable trough to contain ink in its lower part, guiding means at the ends of the trough, a frame carrying a printing roller and having ends engaged by the said guiding means, means under the said frame which press the said frame upward, an innermost frame carried by the printing roller frame, and fitted with an inking roller, and means which press the innermost frame upward to cause the inking roller to bear against the printing roller, a wick extending from the inking roller downward to the ink supply, the trough having, to control the ink level, ink outlet means, the said means being usable for filling purposes.

In witness whereof we have hereunto signed our names to this specification at Melbourne in the State of Victoria, in Australia, this thirtieth day of September, 1925.
